ARTHUR E. MARTOIS, OF COMPTON, CALIFORNIA

TONG OPERATING MECHANISM

Application filed November 12, 1928. Serial No. 318,716.

My invention relates to means for breaking tool-joints of various tubular members used in an oil-well or water-well. A very important use of the invention is in connection with oil-wells, and for this reason the invention will be explained in reference to its use in the oil-well industry.

In the oil-well industry various tubular members are used such as a drill-pipe and pump-tubing, which are extended into the well. Such tubular members consist of lengths of pipe which are secured together by tool-joints. The present method of breaking a tool-joint is to extend a rope 15 from the tong around a cathead which is mounted on the rotary draw-works of the derrick. This present method of breaking tool-joints is very unsatisfactory for the reason that a great deal of danger to the 20 workmen and equipment is involved.

As I have mentioned, the present method calls for the use of a rope, one end of which is connected to the tong, the other end being wrapped around the cathead which is 25 usually mounted on the line-shaft of the draw-works.

The cathead consists of a spool-shaped member, and one used for this purpose is on the end of the draw-works opposite from 30 the driller's position. Owing to its location it is very difficult for the driller to observe the actions of the cathead man in the performance of his duties. When the joint is to be broken, the cathead man is required 35 to throw or loop the rope around the cathead and to apply pressure to the free end of the rope sufficient for the rope to obtain a bite on the cathead. Very often the cathead man becomes tangled in the end of the 40 rope and unless the driller stops the cathead from rotation, serious or fatal injury to the cathead man is liable to occur. Many serious disasters have occurred to cathead men.

Attempts have been made to overcome the difficulty encountered in the type of cathead just mentioned, by introducing automatic catheads which are controlled by friction clutches or other means. These devices 50 when in perfect condition, and operating

as intended, eliminate considerable of the danger inherent in the use of the first-mentioned type of cathead. These automatic catheads, however, have made little progress toward doing away with danger, owing to 55 the fact that when the automatic catheads have been in use but a short time, there is a tendency for the clutches to freeze, making it impossible for the operator to release them. This failure of the automatic 60 catheads converts them into the ordinary cathead first-mentioned above, and revives the same dangers which are encountered in using the first type of cathead.

One of the objects of my invention is to 65 provide a joint breaker which is placed so as to directly engage the tong, there being no intervening parts which are placed under tension.

Another object of the invention is to provide a joint breaker which does not require any flexible connecting members which are liable to break or to tangle.

A further object of the invention is to 75 provide a joint breaker in which the parts are subjected to compression rather than to tension.

In using the catheads mentioned above, it is necessary for the driller to quickly stop the shaft carrying the cathead, when the 80 joint has been broken. This is necessary in order that there be no excessive pull exerted on the rope which is connected to the cathead and to the tong, in order that this rope will not be snapped.

One of the objects of my invention is to 85 provide a joint breaker in which a continued operation thereof after the joint is broken will do no harm to the apparatus itself, or to other apparatus in the well, and which will not harm or injure the workmen.

It is also an object of my invention to provide a joint breaker in which the parts are uniquely designed in order to obtain ruggedness of construction.

It is another object of the invention to provide a joint breaker having the characteristics pointed out heretofore, which is designed so that it may be placed on the rotary 100

table through which the drill-pipe of the well is extended.

It is also an object of the invention to provide a joint breaker which may be readily removed or replaced by the workmen.

It is a still further object of the invention to provide a joint breaker adapted for location adjacent to the tong which is secured to the drill-pipe, and which may be operated from the draw-works or through mechanism of the well by operating mechanism which is not liable to breakage.

Other objects and advantages will be pointed out in the following description.

Referring to the drawings in which the invention is illustrated,

Fig. 1 is a diagrammatic perspective view showing the invention in the manner in which it may be connected to the draw-works of a derrick.

Fig. 2 is an elevational view showing the invention in the manner in which it may be connected to the derrick.

Fig. 3 is an elevational view taken as indicated by the arrow 3 of Fig. 2.

Fig. 4 is a plan view of the invention.

Referring to the drawings in detail, the numeral 11 represents the floor of a derrick, at the central part of which floor is a rotary machine 12, and at the edge of which is a rotary draw-works 13. The rotary machine 12 and the draw-works 13 may be of standard construction, and therefore the parts will only be briefly referred to in this specification, it being understood that various types of this apparatus may be used in connection with the invention.

The rotary machine 12 consists of a base 15 having roller bearings 16 which support a rotary table 17. The rotary table 17 is driven by a pinion gear 18 attached to a shaft 19, the shaft 19 being supported by a unitary bearing structure 20. The rotary table 17 carries pipe-slips 22, and extended through the rotary table 17 is a tubular member in the form of a drill-pipe 23.

The draw-works 13 includes a counter-shaft 25, a line-shaft 26, a drum-shaft 27, and a jack-shaft 28. The various shafts are connected together by chains and sprockets according to standard practice. The jack-shaft 28 carries a sprocket 29, and extended around the sprocket 29 and a sprocket 30 attached to the shaft 19 of the rotary machine 12, is a sprocket chain 31. When the jack-shaft 28 is set in rotation, the sprocket chain 31 is driven with the result that the rotary table 17 is caused to rotate. The line-shaft 26 of the draw-works 13 carries a sprocket 33 around which a power transmitting means or chain 34 is extended. The chain 34 is utilized for driving the joint breaker 35 of my invention, which will now be described.

65. The joint breaker 35 has a frame 37 pro-

vided with a lower horizontal flange 38 adapted to engage the upper surface of the base 15 of the rotary machine 12. Depending from the flange 38 are lugs 39, these lugs 39 extending into pockets or cavities 40 of the base 15. Adapted to lock the lugs in the cavities are pins 43 shown best in Figs. 3 and 4. The upper portion of the frame 37 extends over the pinion 18 and a part of the table 17. The lower portion of the frame 37 is provided with an opening 44 which receives the parts of the rotary machine which we just mentioned.

The frame 37 has a horizontal bearing 45 which journals a horizontal shaft 46. Secured to the outer end of the horizontal shaft 46 is a sprocket 47 around which the sprocket chain 34 is extended. When the sprocket 33 is driven, the chain 34 rotates the sprocket 47 and the shaft 46. The end of the shaft 46 adjacent to the drill-pipe 23 is provided with a worm 50.

The frame 37 has a top vertical bearing 51 and a lower vertical bearing 52. The top bearing 51 is supported by a top wall 53 of the frame, and the lower bearing 52 is supported by an intermediate wall 54 of the frame. These vertical bearings 51 and 52 support a vertical shaft 55. The vertical shaft 55 carries a worm gear 56 which is adapted to mesh with the worm 50. When the shaft 46 is rotated the worm 50 rotates the worm gear 56 and the vertical shaft 55.

The upper end of the vertical shaft 55 carries an engaging means in the form of an eccentric cam 58.

The drill-pipe 23, as mentioned in the preamble of this application, is made up of lengths of pipe which in the drawings are identified by the numerals 60 and 61. The lengths of pipe 60 and 61 are secured together by a tool-joint 62 consisting of a lower-part 63 and an upper-part 64. When the joint is to be broken, a back-up tong 66 is attached to the lower-part 63. The handle 67 of the back-up tong 66 has a rope 68 secured to it, this rope 68 being tied to a stationary member so that the back-up tong 66 and the lower length of pipe 60 cannot rotate.

An upper tong or wrench 70 is applied to the upper-part 64 of the tool-joint 62 in the position shown in the drawings. The tong 70 has a handle 71 which extends outward adjacent to the cam 58, as illustrated best in Fig. 4 of the drawings. After the parts have been arranged as just described, the joint breaker is set into operation.

In order to cause the joint breaker to operate, it is necessary to rotate the sprocket 33 carried by the line-shaft 26. This sprocket 33 may be rigidly attached to the line-shaft, or it may be capable of rotating thereon and a clutch 74 may be provided for locking the sprocket 33 to the line-shaft.

26 whenever it is desired to operate the joint breaker. When the sprocket 33 is operated, the sprocket chain 34 causes the sprocket 47 and the shaft 46 to rotate. The 5 worm 50 and the worm gear 56 cause the vertical shaft 55 to rotate.

When this rotation occurs the cam 58 is rotated preferably in a direction indicated by the arrow 76 of Fig. 4. The external or 10 peripheral surface 77 which engages the handle 71 of the wrench 70 presses against this handle, and as the cam turns, the handle is gradually moved in the direction indicated by the arrow 78 until the cam reaches 15 a position indicated by dotted lines 80, and until the handle itself reaches a position indicated by dotted lines 81. When the handle is thus swung, the entire wrench 70 and the length of drill-pipe 61 to which the 20 handle is attached, are rotated this angular distance. This amount of rotation is sufficient to break the joint 62 and therefore the lengths 60 and 61 may be readily separated.

It will be seen that in using my invention 25 the lives of the workmen are not endangered, and there is no danger of the mechanism in the well being damaged due to any breakage of parts or entanglement of equipment.

30 The engaging-means or cam 58 exercises a pressure against the tong handle 71 and in this manner breaks the joint. It is one of the purposes of my invention to design the apparatus so that there are no inter- 35 connecting flexible members which are placed under a tension. This feature greatly reduces any danger to the workmen or equipment since if any breakage should occur, there are no parts liable to fly around 40 the derrick as there would be if a flexible member such as a rope or cable placed under tension were to break, as would often occur in using the cathead mechanism for breaking joints.

45 It is very important to the invention that the joint breaker be directly connected to the tong handle 71.

With the design of joint breaker which I provide, enormous forces may be used for 50 breaking a joint, and those joints which are difficult to break in the ordinary joint breaking equipment are broken by the mechanism of my invention with substantially the same ease that easily broken joints are broken.

55 The joint breaker 35 is supported directly on the rotary machine 12, and it therefore has a solid foundation. When the joint breaker is not in use the pins may be removed and the entire joint breaker may 60 be removed from the rotary machine and placed at the side of the derrick so that other operations in the well may be carried on without any interference by the joint breaker. The chain 34 may be elevated 65 out of the way on one side of the derrick.

The particular design of apparatus illustrated in the application is only one form in which my invention may be embodied.

My invention in its broadest conception 70 consists in a joint breaker adapted to directly engage the wrench or tong or other member which is attached to the drill pipe, and through which pressure is applied for breaking a joint.

My invention also broadly resides in any 75 construction in which the joint is broken by means of a part placed under compression rather than a part placed under tension.

It should be noted that by rotating the 80 cam 58 by means of the worm 50 and the worm gear 56, I provide an irreversible drive means which prevents a reverse rotation of the cam 58 in case the chain 34 should be broken. I thus eliminate the accident hazard which would occur should the 85 wrench 70 be suddenly released when under the strain incident to breaking the joint.

I claim as my invention:

1. In combination: a pipe having a joint; means for holding one part of said pipe 90 from rotation; a rotary machine through which said pipe extends; a wrench attached to the other part of said pipe, said wrench having a handle; a frame located adjacent to said pipe and supported by said rotary machine; a shaft carried by said frame; a cam on said shaft, said cam being arranged to directly engage said handle of said wrench and to turn same; and worm gear means for turning said shaft and said cam. 100

2. In combination: a pipe having a joint; means for holding one part of said pipe from rotation; a rotary machine through which said pipe extends; a wrench attached to the other part of said pipe; a frame carried by said rotary machine; a vertical shaft carried by said frame; a cam on said shaft adapted to directly engage said wrench and to turn same; a worm gear on said shaft; a horizontal shaft carried by 110 said frame; a worm on said horizontal shaft operatively engaging said worm gear; and operating means for turning said horizontal shaft.

In testimony whereof, I have hereunto 115 set my hand at Los Angeles, California, this 6 day of Nov., 1928.

ARTHUR E. MARTOIS.
